SAFETY RAZOR

William L. Mills, Waco, Tex.

Application March 11, 1946, Serial No. 653,546

3 Claims. (Cl. 30—69)

1

This invention relates to razors and more particularly to a safety razor including separable plates between which a blade is mounted and a handle threaded to a stem carried by one plate and passing through an opening in the other plate, it being one object of the invention to provide the razor with plates so formed that a narrow blade may be firmly clamped between the plates and prevented from slipping out of a position in which its cutting edge will be held parallel to front edges of the plates and also parallel to a bar constituting a portion of a guard which is pivoted to one plate and yieldably held against swinging movement so that it will assume a position allowing the blade to cut a beard while shaving but not cut a person's face.

Another object of the invention is to provide a safety razor wherein the blade has end tongues by means of which it may be readily held and inserted or removed from between the plates.

Another object of the invention is to so form the guard and so form one plate that swinging movement of the guard towards a protruding sharpened edge of the blade will be limited and the blade prevented from assuming an angle in which it may cut a person's face while shaving.

Another object of the invention is to provide the razor with a spring mounted longitudinally of the front plate with its ends projecting therefrom for engagement with arms of the guard to urge the guard towards the front plate.

Another object of the invention is to provide a safety razor consisting of plates and a handle so formed that while the razor may be taken apart for thorough cleaning and drying the plates will be firmly held together for clamping a blade between them when the handle is applied and screwed along the stem into contact with the front plate.

The invention is illustrated in the accompanying drawings wherein:

Fig. 1 is a side view of the improved razor.

Fig. 2 is a view looking down upon the razor.

Fig. 3 is a view taken along line 3—3 of Figure 1.

Fig. 4 is a sectional view taken along line 4—4 of Figure 2.

Fig. 5 is a rear view of the razor.

Fig. 6 is a sectional view taken along line 6—6 of Figure 2.

Fig. 7 is a view taken along the line 7—7 of Figure 6.

Fig. 8 is a sectional view taken along line 8—8 of Figure 6.

Fig. 9 is a perspective view of the blade.

2

Fig. 10 is a top view of a modified form of razor. Fig. 11 is a side view of the razor shown in Figure 10.

Fig. 12 is a view taken along line 12—12 of Figure 11.

Fig. 13 is a sectional view taken along line 13—13 of Figure 10.

Fig. 14 is a rear view of the razor.

Fig. 15 is a sectional view taken along line 15—15 of Figure 12.

Fig. 16 is a sectional view taken along line 16—16 of Figure 15.

Fig. 17 is a view looking at the front plate with the rear plate removed.

Fig. 18 is a view looking at the inner face of the rear plate.

The razor illustrated in Figures 1 through 9 has a front plate 1, a rear plate 2, and a handle 3 which is screwed upon a threaded stem 4 carried by the rear plate 2 and removably engaged through an opening 5 formed midway the length of the front plate 1. The rear plate 2 also carries pins 6 located near its end and passing through openings 7 formed in the front plate. Ends of

20 the pins are upset to limit movement of the plate 2 away from the plate 1, but the pins are of such length that plate 2 may be shifted away from the plate 1 when the handle is loosened upon the stem 3 and thus provide space between the two plates. The lower edge portion of the front plate is smooth and at its ends this plate is pro-

23 vided with tongues or fingers 8 which project downwardly and are of such length that they project beyond the sharpened edge of a blade 9 when the blade is fitted into the space between the plates and the handle then tightened upon the stem 3 to move the plate 2 towards the plate 1 and into clamping engagement with the blade. This blade 9 is formed as shown in Figure 9 and

26 has its rear edge formed with recesses 10 and 11 to receive the stem 4 and the pins 6 which serve to prevent the blade from slipping longitudinally out of its proper position between the plates. This also assures parallel relation of

30 the cutting edge of the blade with lower edges of the plates and causes the sharpened edge of the blade to protrude from the plates the same distance throughout its length. Tongues 12 project from ends of the blade and are of such length that they protrude from ends of the two plates.

35 Therefore the blade may be held by its tongues 12 and readily slid into place between the plates, and by grasping these tongues a blade may be easily withdrawn from between the plates.

40 In order to prevent the blade from cutting a

45

45

50

55

person's face while shaving there has been provided a guard 13 consisting of a bar of stiff metal having arms 14 at its ends. The bar 13 is of greater length than the plates and its arms 14 of such length that pins 15 projecting from ends of the upper edge of the front plate 1 may engage through openings formed in the arms and pivotally mount the guard for swinging movement from the position shown in full lines in Figure 1 towards the position indicated by dotted lines. 10 The tongues 8 and the tongues 12 overlap the upper faces of the bar and the arms of the guard and serve to limit rearward swinging movement of the guard beyond the position shown in full lines in Figure 12. In order to normally hold the 15 guard in abutting engagement with the tongues 8 and 12 and yieldably resist forward movement of the guard there has been provided a spring 16 consisting of a strip of resilient metal having its intermediate portion fixed to the front face of 20 plate 1 and extending longitudinally thereof with its free end portions 16' projecting from ends of this plate and extending across the arms of the guard as shown in Figure 3. The spring urges the guard rearwardly but allows it to be swung forwardly. Therefore when the razor is in use the guard and the blade may have movement relative to each other and the blade may be disposed in such an angularly adjusted position that its sharp edge may cut through whiskers without cutting a person's face while shaving. When the handle is unscrewed from the stem 4 the plates may be separated and the blade removed so that the razor may be thoroughly cleaned and dried and then reassembled.

In Figures 10 through 18 there has been illustrated a modified construction. In this embodiment of the invention the front and rear plates 17 and 18 clamp a blade 19 between them with tongues 20 of the blade projecting from ends of the plates and the sharpened edge of the blade projecting from the teeth 21 along the front edge of the plate 18 between the tongues 22. A recess 23 is formed midway the length of the rear edge of the blade to receive a portion of the stem or post 24 which is carried by the plate 18 and passes through the opening 25 of front plate 17 for engagement in the threaded socket of the handle 26. A rib 28 formed along the inner face of the plate 18 engages in a groove 29 formed in the inner face of the plate 17 and serves to hold the two plates against turning movement about the post. The rear edge of the blade bears against the rib and causes the blade to be held against tilting and maintains its sharpened edge parallel to front edges of the plates.

A guard is provided to prevent cutting of a person's face due to improper engagement of the sharpened edge of the blade with the skin. This guard 30 consists of a bar of stiff metal which is of greater length than the jaws or plates 17 and 18 and is formed at its ends with arms 31 having openings near their ends to receive the pins 32 at ends of the plate 17 and pivotally mount the guard for swinging movement from the position shown in full lines in Figure 11 towards the position indicated by dotted lines. This guard is to bear against the skin while shaving and serve as a fulcrum across which the razor is rocked to dispose the blade in proper angular relation to the 70 skin so that it may cut the beard without cutting the skin. It is necessary that the guard be urged to the position shown in full lines in Figures 11 and 13 but allowed to swing about the pins 32 during use of the razor and in order to urge the 75 guard and the tongues of the front jaw having

guard towards its normal position there has been provided a spring 33 formed from resilient sheet metal. This spring is mounted against the outer face of the plate 17 and formed with an opening registering with the opening of the plate through which the post passes, the spring being of such length that its end portions 33' engage across the arms 31 of the guard and yieldably hold the guard in its normal position. When the handle is unscrewed from the post or stem 24 the plates or jaws 17 and 18 may be separated and the razor thoroughly cleaned and dried and then reassembled for use.

Having thus described the invention, what is claimed is:

1. A safety razor comprising front and rear jaws, a post carried by the rear jaw and passing through the front jaw, a handle threaded to said post for holding the jaws in clamping engagement with a blade disposed between the jaws, a guard extending longitudinally of the front jaw in spaced parallel relation to the front edges of the jaws and having arms extending rearwardly from its ends and pivoted to opposite ends of the rear edge of the front jaw, tongues extending forwardly from opposite ends of the front edge of the front jaw for engaging across opposite ends of the guard and limiting movement of the guard towards the jaw, and a spring mounted against the front face of the front jaw and extending longitudinally adjacent the rear edge thereof with its ends projecting from ends of the rear edge of the front jaw and engaging across under faces of rear ends of the arms of the guard forwardly of the pivots to yieldably hold the guard in engagement with the tongues of the front jaw.

2. A safety razor comprising front and rear jaws, a post carried by the rear jaw and passing through the front jaw, a handle threaded to said post for holding the jaws in clamping engagement with a blade disposed between the jaws, a guard consisting of a bar extending longitudinally of the front jaw in spaced parallel relation to the front edges of the jaws and having rearwardly extending arms at its ends pivoted at their rear ends to opposite ends of the rear edge of the front jaw, abutments extending forwardly from the front edge of the front jaw for limiting swinging movement of the guard towards the front jaw, and a spring carried by the front jaw and having portions projecting from ends thereof and extending across under faces of the arms of the guard near pivoted ends thereof for yieldably resisting movement of the guard away from the jaw.

3. A safety razor comprising front and rear jaws, a post carried by the rear jaw and passing through the front jaw, a handle threaded to the post and holding the jaws together, a blade between the jaws having a sharpened edge protruding from lower edges of the jaws and having end portions formed with integral tongues extending from ends of the body of the blade and projecting beyond the ends of the jaws, tongues projecting downwardly from ends of the lower edge of the front jaw and spaced outwardly from ends of the cutting edge of the blade, a guard including a bar extending longitudinally of the jaws and spaced downwardly from ends of the lower edges of the jaws and the protruding edge of the blade and arms extending upwardly from ends of the bar and pivoted to the front jaw at opposite ends of the upper edges, the tongues of the blade extending across the upper surfaces of the arms of the 75 guard and the tongues of the front jaw having

overlapping engagement with end portions of the bar to limit swinging movement of the guard towards the jaws, and a spring consisting of a strip of resilient sheet material secured to the front jaw and extending longitudinally thereof with its end portions projecting from ends of the upper edge portions of the jaws and engaged across the under faces of the arms to yieldably resist movement of the guard away from the jaws and the blade.
